4 Claims

The present invention relates to a shelf edging or a trimming for application to the edge of shelves and the like, said shelf edging being commonly used to decorate kitchen shelves.

These shelf edgings also form a protective lining for the rough edges of shelves and the like. Some shelf edgings are made of paper, but must be frequently replaced as they are not washable. Shelf edgings made of washable plastic material, such as polyvinyl and the like, are becoming into general use.

These plastic shelf edgings generally consist of an elongated piece having one longitudinal marginal portion shirred and stitched in overlapping position to a supporting strip, which is itself provided at the back thereof with means for adhering the edging to the edge of a shelf or the like, said means generally consisting of a coating of glue adapted to be moistened for adhesion.

The elongated piece is generally printed with an ornamental design or pattern, but the glue-coated strip is of one colour, as it is impossible in production to carry the decorative pattern on the supporting strip and match the pattern of the strip with that of the elongated piece, so much as the latter is shirred.

The resulting shelf edging has a rather poor ornamental effect, which would be even worse if the supporting strip had its own decorative pattern printed thereon.

It is, therefore, the general object of the present invention to provide an edge trimming for shelves and the like, more particularly kitchen shelves, which has a highly decorative effect obtained by the application of coloured threads to the supporting strip of the shelf edging, in accordance with any desired pattern, said coloured threads or yarns adding body or relief to the supporting strip due to the fact that it protrudes forwardly of the same, the resulting decoration being in three dimensions.

Another object of the present invention resides in the provision of a highly decorative and ornamental shelf edging or edge trimming, in which the same stitching threads which are used to secure the elongated piece to the supporting strip, serve also to secure the decorative or ornamental yarns to the front face of the supporting strip.

Another important object of the present invention resides in the provision of a shelf edging of the character described, which is only slightly more expensive to manufacture than similar types of shelf edging without ornamental yarns thereon, due to the fact that the stitching together with the elongated piece and supporting strip, the shirring of the elongated piece and the application of the ornamental yarns are all carried in one sewing operation.

The foregoing and other important objects of the present invention will become more apparent during the following disclosure and by referring to the drawings, in which:

FIGURE 1 is a front elevation of a portion of a shelf edging in accordance with a first embodiment of the invention;

FIGURE 2 is a front elevation of a portion of a shelf edging in accordance with a second embodiment;

FIGURE 3 is a cross-section, taken along line 3—3 of FIGURE 1 and showing how the edging is applied to the edge of a shelf or the like;

2

FIGURE 4 is a cross-section, taken along line 4—4 of FIGURE 2, the edging being applied to the edge of a shelf; and

FIGURE 5 is a detailed partial plan view showing how an ornamental yarn is stitched in position to the front face of the supporting strip.

Referring now more particularly to the drawings in which like reference characters indicate like elements throughout, the first and second embodiments shown are of substantially identical construction; only the pattern of the ornamental yarns is differing.

Referring to the second embodiment shown in FIGURES 2, 4, and 5, the shelf edging comprises an elongated flexible piece 1, made of polyvinyl material or other washable synthetic plastic, which is secured to a support strip 2, the latter having on the front face thereof coloured ornamental yarns 3, 3', and 3" secured to strip 2 by lines of stitching 4, 4', 4" and 4'', which also serve to secure strip 2 to elongated piece 1 and to a glue-coated strip 6.

The outer longitudinal edge 5 of piece 1 is preferably sheared and scalloped to provide a decorative effect. The other longitudinal marginal portion of elongated piece 1 overlaps the back face of strip 2 with the interposition of a glue-coated strip 6, which extends the entire length and substantially the full width of the support strip 2.

The coat of glue 7 on strip 6 faces rearwardly of strip 2 and is exposed.

The upper and lower longitudinal marginal portions of support strip 2 are folded back, as shown at 8 and 8' respectively.

The upper line of stitching 4 serves to secure the glue-coated strip 6 to the folded back upper marginal portion 8 of support strip 2 and also the upper ornamental yarn 3 to the front of support strip 2.

The intermediate lines of stitching 4' and 4'' serve to secure a pair of intermediate ornamental yarns 3' and the glue-coated strip 6 to support strip 2. In addition, line of stitching 4'' secures the upper marginal portion of the elongated piece 1 to support strip 2; the lower line of stitching 4''' secures the elongated strip 1 and also the lower ornamental yarn 3'' to the lower folded marginal portion 8' of support strip 2.

The upper marginal portion of elongated piece 1 is shirred or gathered together, as shown at 9, and the shirring is effected simultaneously, as said elongated piece is sewn to the support strip 2 by lines of stitching 4' and 4'''.

The upper and lower lines of stitching 4 and 4''' are made in accordance with a slightly zigzag path, as shown in FIGURE 5, so as to engage the support strip 2 alternately on both sides of the ornamental yarns 3 and 3'', so that the latter will have a wavy form.

There are two intermediate ornamental yarns 3' which are stitched each in a wavy form, the yarns crossing each other in their portion intermediate their zone stitched to support strip 2.

The edge trimming in accordance with this embodiment can be produced in one operation on a suitable sewing machine.

The trimming is used in the following manner:

A suitable length of the trimming is cut, the glue 7 is moistened and the support strip is then pressed against the edge face 10 of a shelf 11, or the like, such that the top of the trimming will be substantially aligned with the top of edge face 10.

A highly decorative effect is achieved due to the combination of the shirred elongated piece 1 with the raised ornamental design provided by the decorative yarns 3, 3', and 3''.

Preferably, the yarns 3 and 3'' will be of the same colour, which will be different from that of yarns 3'.

The edge trimming in accordance with the first embodiment shown in FIGURES 1 and 3 comprises, as in the first embodiment, elongated piece 1, support strip 2, glue-coated strip 6, and three ornamental yarns 12, 13, and 14, secured to front face of support strip 2 by the four lines of stitching 4, 4', 4'', and 4'''.

The pair of intermediate ornamental yarns 13' have also a wavy or zigzag shape and are secured in position at their apices by lines of stitching 4' and 4''. Said pair of intermediate ornamental yarns 13' cross each other at their portions intermediate the lines of stitching 4' and 4'', as in the second embodiment.

The elongated piece 1 of the first embodiment is gathered together or Shirred at the lines of stitching 4'' and 4''' and the strip 2 has its marginal portions 8 and 8' folded back, as in the second embodiment. Piece 1 of the first embodiment has preferably a scalloped and sheared lower edge 5.

Two embodiments have been illustrated to show that the trimming in accordance with the present invention can be provided with a plurality of decorative patterns formed by different arrangements of the ornamental yarns applied to the front face of support strip 2.

The first embodiment, as the second, can be made in one operation by a suitable sewing machine.

While a preferred embodiment in accordance with the present invention has been illustrated and described, it is understood that various modifications may be resorted to without departing from the spirit and scope of the appended claims.

What I claim is:

1. Shelf edging comprising an elongated piece of flexible material, a flexible support strip having the back face of one longitudinal marginal portion overlapping a longitudinal marginal portion of said elongated piece, at least two spaced longitudinal lines of stitching securing said elongated piece to said support strip, said longitudinal

marginal portion of said elongated piece being Shirred by said lines of stitching, coloured yarns secured to the front face of said support strip by said lines of stitching and forming a decorative pattern, a glue-coated strip disposed behind said support strip, interposed between the overlapping longitudinal marginal portions of said support strip and elongated piece, and protruding from said marginal portion of said elongated piece to be exposed, and additional lines of stitching securing said exposed portion of said glue-coated strip to said support strip and also securing said ornamental yarns to said support strip.

2. Shelf edging as claimed in claim 1, wherein the longitudinal edge of said elongated piece opposite to the one secured to said upper strip, is secured and scalloped.

3. Shelf edging as claimed in claim 1, wherein both longitudinal marginal portions of said support strip are folded back to extend between said glue-coated strip and said support strip.

4. Shelf edging as claimed in claim 2, wherein both longitudinal marginal portions of said support strip are folded back to extend between said glue-coated strip and said support strip.
